UNITED STATES PATENT OFFICE.

WILLIAM E. GREENAWALT, OF DENVER, COLORADO.

APPARATUS FOR TREATING LIQUIDS WITH GASES.

Application filed April 2, 1923. Serial No. 629,362.

The invention has as its object the effective atomization, or fine subdivision, of gas in liquid. It finds effective application in the flotation treatment of ores; in the pneumatic agitation of liquids and ore pulps; and the application of corrosive gases, such as sulphur dioxide or chlorine, to the treatment of copper, gold, and silver ores.

The description of the invention will be more particularly directed to the flotation treatment of ores.

In the flotation treatment of ores, excellent results have been obtained by applying the air, or gas, to the ore pulp, through a porous material in the lower portion of the tank containing the ore pulp. In doing this, certain difficulties have arisen; among which may be mentioned the delicate nature of the porous material if it is made of woven fabric, the clogging of the pores if inorganic porous material is used, and the settling of the sands on the porous material and consequent unequal distribution of the air in worn or clogged porous material.

To overcome these difficulties, jets of air have been injected into the liquid, and the impingement of the air against the liquid subdivides the air and gives encouraging results, although these results are far from being as satisfactory as theoretical conditions would indicate.

I have found that if jets of air, or gas, are mixed with the liquid, and the mixture is injected into the surrounding liquid in the tank, a very satisfactory atomization can be accomplished, especially if these jets of gas and liquid are directed against one another, or arranged to inter-penetrate one another in the liquid in the tank. It has been found, by this arrangement, that the injecting of the gas, in this way, can be made sufficiently energetic to prevent sands from settling, even in flat bottom tanks, and that the construction of the apparatus can be made in large units, which has an important bearing in the practical and economic operation. In the treatment of ores with acid solutions or with corrosive gases, the ore pulp may be treated and agitated by means of air or other gas by making the gas diffusing members of some acid proof, or acid resisting material, such as antimonial lead, or ferrosilicon.

The advantage of getting a fine atomization of the gas, without a porous material, is evident.

The invention will now be described in detail, reference being made to the accompanying drawings, in which Fig. 1, represents a plan of the apparatus as applied to the flotation treatment of ores; Fig. 2 the corresponding longitudinal section; Fig. 3 the corresponding transverse section; Fig. 4 a longitudinal section of the invention adapted to treat liquids with corrosive gases; Fig. 5 a detail in vertical section of the atomizer, injector, or gas impregnator, and Fig. 6 the corresponding horizontal section on the line 6-6 of Fig. 5; Fig. 7 a detail vertical section of a modified form of atomizer, or injector, and Fig. 8 the corresponding horizontal section on the line 8-8 of Fig. 7; Fig. 9 a detail of the bottom of the tank similar to that shown in Fig. 3; Fig. 10 a cross section of a modification of the apparatus as applied to the flotation treatment of ores; Fig. 11 a detail in vertical section of the corresponding atomizer and lower portion of the tank; Fig. 12 a cross section in detail of the atomizer or injector; Fig. 13 a longitudinal section of a modified apparatus; Fig. 14 a horizontal section of one end of Fig. 13; Fig. 15 a detail in vertical section showing the relation of the atomizers to the tank; Fig. 16 a modification of the invention, in vertical section, as applied to round tanks; and Fig. 17 is a vertical section of a modification of the invention as applied to a continuous flow of gas and liquid in which both the gas and liquid are under super-atmospheric pressure.

Referring to the drawings; 1 is a tank adapted to contain the liquid, or ore sludge, to be treated. The tank is preferably divided into sections 1^a, 1^b, 1^c, and 1^d, by the vertical partitions 2, so that the liquid may flow progressively through the tank from one section to the next, for any number of sections; for this purpose the partitions have communicating openings 2^a, which are intended to be large enough to maintain practically the same liquid level in all the sections composing the tank. The tank is provided with a liquid inlet 3, with a weir overflow outlet 4, and with an underflow outlet 5 to take the heavier particles of insoluble matter which cannot be rejected through the weir overflow outlet 4. The underflow outlet 5 has a regulating valve, by means of which a small steady stream can be made to flow through the underflow outlet to take care of the heavier particles of

suspended matter, while the liquid and slimes overflow over the weir, and this weir is made abundantly large so that any irregularity in the feed will not cause an appreciable change in the liquid level in the tank.

In the bottom of the tank, in the respective compartments, are gas chambers 6, which are supplied with gas under pressure 10 through the gas pipe 7, and the flow of gas into the respective gas chambers may be regulated by the valves 10. The flow through the gas main 7 may be regulated by the valve 11. Communicating with each of 15 the gas chambers 6 are atomizers, gas distributors, or injectors, 9, arranged and designed so that the gas in the gas chambers 6 is forced out through discharge passages, and in being forced out, acts as an injector, 20 to suck some of the liquid in the tank into the interior of the atomizer, where the gas and liquid are mixed, and the mixture of gas and liquid is then ejected into the surrounding liquid in the tank. The gas ejected 25 in this way is brought into a very fine state of subdivision, or atomization; much finer than is obtainable by merely ejecting a stream of gas alone into the liquid. The impetus of the liquid mixed with the ejected 30 gas carries the gas a comparatively long distance from the ejector, and by arranging these ejectors so that the streams of the mixture of gas and liquid impinge, intersect, or penetrate one another, a fairly fine and 35 uniform distribution of the gas may be made all over the bottom of the tank, and the finely divided gas, ascending through the liquid, offers, it is believed, ideal conditions for flotation, for impregnation, and for 40 heating and cooling of the liquid, without the use of rotary mechanism.

The gas atomizers may be described in detail by referring to Figs. 5 and 6. The compressed gas from the submerged gas 45 chamber 6, is forced through the pipe 16 into the gas discharge passages 17, and through the gas discharge passages 17 into the gas and liquid discharge passages 19. As the gas is injected from the discharge 50 passage 17 into the discharge passage 19, it sucks liquid from the tank into the interior of the atomizer, through the ducts 18, working somewhat like an injector, and the mixture of gas and liquid is then ejected into the 55 surrounding liquid in the tank.

Any number of these atomizers may be screwed into the gas chamber in the bottom of the tank, and they are preferably arranged so that radiating jets, or streams, of 60 gas and liquid, mix, impinge, and penetrate, so as to bring the gas in a fine state of subdivision, give a fairly uniform distribution of the gas, and prevent violent surging of the liquid. Violent surging of the liquid 65 is detrimental to flotation.

The size of the jets, or streams, of gas and liquid will be mostly determined by the material to be treated. If liquid alone is to be treated the jets may be quite fine and quite numerous, for, in that case there is no danger 70 of the atomizers becoming clogged or of sand settling in the bottom of the tank. If the material to be treated is ore pulp, the jets of gas and liquid should be larger and stronger, at least strong enough to prevent 75 any settling of sands.

The pressure under which the gas should be delivered to the gas chamber will also depend largely on the material to be treated. For the sake of economy the gas should be 80 delivered at the lowest pressure which will give the desired atomization and agitation.

In Figs. 7 and 8 is shown a modification of the atomizer shown in Figs. 5 and 6. The gas is delivered into the interior of the atomizer through the pipe 20, and is ejected through a multiplicity of ducts, or discharge passages, 21 into the general channel formed by the upper and lower plates. This general channel is designated by 22 and 23. 90 The stream of gas and liquid is ejected outwardly around the entire periphery of the atomizer. In this type of atomizer, as also in the other type, the gas may be introduced directly into the interior of each atomizer, 95 through the pipe 20, and the flow of gas to each atomizer may be under direct control by a valve (not shown). The atomizer may rest directly on the bottom of the tank. This type of atomizer is preferred where violent 100 agitation is required in the presence of corrosive gases or corrosive liquids, or for the agitation of ore pulp containing rather coarse particles which would be inclined to settle under mild agitation. These atomizers may 105 be made quite large; from one foot to three feet in diameter might be considered reasonable sizes. They could also easily be made of acid resisting metal.

Fig. 9, shows a detail of the lower portion 110 of the tank, in which the atomizers are arranged at different elevations, as shown in plan at 1^a and 1^b, Fig. 1; and with the gas inlet pipe 7^a connected with the gas chamber 6 through the top instead of through the 115 bottom. Such an arrangement as shown in Fig. 9, will avoid any complications due to making connections through the tank. The gas chambers, as shown in Fig. 9, can be raised and lowered, with the atomizers attached, and thus repairs and inspections can 120 easily be made.

In Fig. 4, the gas is exhausted from the upper portion of the tank and forced in the lower portion by means of the exhausters 30, and both the gas and the material being treated are flowed progressively from one section to the next through the tank. The gas inlet is shown by 31 and the excess 125 gas outlet by 32. This type of apparatus 130

can be constructed in very large units. A tank, for example, 15 feet wide, 20 feet deep, and 100 feet long, would treat from 2400 tons to 4800 tons of ore per day of 24 hours, with the time of treatment of one and two hours respectively. This is made possible on the basis that a flat bottom tank can be used, and that settling of the ore particles can be avoided by the means described, and 10 that the flow of ore pulp can be made progressively from the tank inlet to the tank outlet.

Fig. 10 shows a modification of the invention, as applied to flotation, in which 15 two atomizers are placed at the sides of the tank in opposite relation, so that the streams of gas and liquid impinge, or intersect, or penetrate, one another, and so that the gas is projected from one side of the tank 20 against the other side. Better results are usually obtained if a grating, or perforated member, is placed above the gas streams in the lower portion of the tank. This somewhat confines the sphere of action, with the 25 result that the gas particles are more minutely subdivided, or atomized, and with the additional advantage that surging is either avoided or greatly reduced. The grating is shown by 29, the atomizer by 24 30 and the gas supply pipe by 25.

A detail section of the lower portion of the tank is shown in Fig. 11. The gas is introduced under pressure into the injector, or atomizer, 24 through the gas supply pipe 25, and is ejected through the gas discharge pipe, or nozzle, 28, into the discharge passage 27. In doing this, some of the liquid of the tank is sucked into the atomizer through the ducts 26, and is ejected with the 40 gas. The impetus given to the stream of gas and liquid ejected from the atomizer, by the gas pressure in the pipe 25, carries the stream of gas and liquid to the other side of the tank, while at the same time 45 small gas bubbles are diffused through the entire lower portion of the tank. The streams, impinging, or penetrating, one another, greatly assists in the diffusion of the gas bubbles.

50 The atomizers are intended to be fairly close together, on each side of the tank, so as to give a uniform distribution of the gas horizontally, in the lower portion of the tank.

55 Fig. 12, shows a detail section through the atomizer on the line 12—12 of Fig. 11. 28 indicates the gas discharge passage and 26 the liquid inlet ducts.

In the flotation treatment of ores, it is 60 desirable to have a somewhat quiet zone 12 (Figs. 3 and 10). This is formed by baffles 13 and the projections 14, so arranged that the mineral froth may overflow into a launder, and the gangue particles and middlings may descend into the main body of

the tank through the opening 15, to be again and again acted upon by the ascending atomized gas, until finally, the material will be eliminated from the tank either as mineral froth, through the overflow 12, or 70 through the gangue and liquid overflow 4, or underflow 5.

If the atomizers are to be positioned fairly close to one another, the arrangement shown at 1^a and 1^b, Fig. 1 is preferred. It 75 is also, in that case, preferred to place alternate atomizers at different elevations, as shown in Fig. 9.

Considerable difficulty has been encountered in the treatment of ore sludge with 80 air jets on account of the jet outlets becoming clogged with ore particles. This is especially likely to happen after an unexpected shut-down. This is overcome by protecting the jet, or gas, outlets, as shown in 85 Figs. 5 and 7. If the air is shut off, and the sands settle, it is not probable that the sand can obstruct the gas outlet so that no gas will flow when the gas pressure is turned on, and once the gas begins to flow, all obstructing sands in the liquid discharge passages are quickly removed.

In the flotation treatment of ores, it is desirable to have the communicating passages between the various compartments 95 fairly low in the tank, as shown in Figs. 2 and 3. This serves two useful purposes: the sands are more easily advanced from one compartment to the next; and a mineral 100 particle, once floated, will have to descend against the ascending atomized gas in order to escape. In this way the entirely barren gangue is quickly worked through the apparatus, while the mineral particles which 105 are not readily floated, are also not readily eliminated, and can be given a thorough treatment.

Referring to Fig. 13; the tank is made with offsets corresponding with the vertical partitions 2 which divides the tank into sections, and a series of atomizers projected through these offsets in the bottom of the tank. The stream of gas and liquid ejected from the atomizers sweep the bottom of the tank, so that the heavier gangue matter is 115 readily moved toward the outlet and eliminated. The mineral is floated toward the surface, and before any particle of mineral, once floated, can escape, it will have to descend against the ascending atomized gas. The baffles 35 are intended to confine and 120 distribute the gas in the lower region of the tank so as to prevent surging at the surface, and also to move the heavier particles of gangue through the tank. Fig. 14 shows the corresponding horizontal section of one end of the tank, showing the series of atomizers arranged so as to give a horizontal distribution of the gas in the lower portion of the tank. The arrangement of the atom-

130

izers is shown in detail in Fig. 15. It is preferred to attach the outside member, or casting 30' to the tank, as shown. This casting 30' is made so that a pipe, or nozzle 33, may be inserted into it from the outside.

Fig. 16 shows the application of the invention to a round tank. The atomizers 30' are arranged about the periphery of the tank, in the lower portion, and preferably very close to the bottom. The intersecting jets of gas and liquid give a good distribution and atomization of the gas. The lower arms 39, rotated by the shaft 38, work the heavier sands toward the outlet 41. The upper arms 40, skim the mineral froth from the top of the liquid. The liquid level is maintained by the weir overflow 4. It will ordinarily be desirable to have a number 20 of these tanks in series for effective flotation.

In the modification shown in Fig. 17, the gas is applied under pressure to a continuous flow of liquid under pressure through the apparatus. This modification is particularly effective in the oxidation or reduction of salts of the variable valent elements in solution. For example, the reducing action of sulphur dioxide in the reduction of ferric salts in copper leach solutions is not very rapid at ordinary temperatures and atmospheric pressure. When, however, the pressure is increased the reduction of the ferric salts is very rapid and complete, and at elevated temperatures, even the copper may be precipitated from sulphate solutions as the elemental metal. The application of a gas to a liquid, under pressure, is well known, but the application of the gas, where both the gas and liquid are under pressure and flowing in continuous streams, and in which the gas in finely subdivided particles is forced up through the liquid under a gas pressure at the top, appears to present new possibilities.

Referring to the modification shown in Fig. 17, 50 represents a tank adapted to contain the liquid and to confine a gas under pressure above the liquid as shown by 51. This tank may be made of steel for non-corrosive liquids, and of steel lined with lead for corrosive liquids. 62 is a tower adapted to contain liquid, and the height of the liquid will be determined by the pressure of gas desired. 53 shows a gas generator, and the gas may be supposed to be sulphur dioxide. The gas is exhausted from the generator 53 through the pipe 57 by means of the exhauster-blower 54, and forced through the pipe 58, through the injectors 60 and into the liquid in the lower portion of the tank. The valve 59 is supposed to be closed. The injectors may be similar to those shown in Fig. 15. The gas, ascending through the liquid against super-

atmospheric pressure and with its reducing power greatly increased, escapes at the top of the liquid into the gas space 51 until sufficient pressure has accumulated to force it through the column of liquid in the tower 62. The valve 59 being closed, the gas, under pressure, is forced through the pipe 61 into the lower portion of the tower 62, and escapes through the liquid in the tower at a pressure corresponding to the height 75 of the liquid, into the space 63 in the upper portion of the tower. From the tower the gas may be exhausted by the exhauster-blower 67 and forced under pressure into another tank 70, and so on for as many 80 tanks as desired, until the gas is sufficiently consumed and the liquid sufficiently treated. The liquid flows into the first tank through the inlet pipe 72, and from the first to the second tank through the connecting pipe 73, 85 and so on for the entire series of tanks for as many tanks as desired. The liquid level may be maintained in the tanks by any of the well known methods, such as a weir overflow in the last tank, or by closely regulating the inflowing and outflowing streams of liquid. To compensate for the difference in pressure which might arise due to variations in the speed of the exhauster-blowers, or to compensate for the consumption of gas in the different tanks, valves 64 and 65 are placed at the top of the towers 63: one of these valves is arranged to blow off excess gas, and the other is arranged to take in air or gas if the pressure falls below the amount desired. Manifestly, the finely sub-divided, or atomized gas, under these conditions, will have a greatly increased effect in oxidation, in reduction, heating, cooling, etc. It has been ascertained by careful experiments, that very finely atomized gas, even under atmospheric pressure, is from four to five times as effective as gas simply bubbled in the liquid, or applied as in the well known Pachuca tank, where the gas is simply introduced through an ordinary pipe and circulation induced through a large central tube within the tank.

I claim:

1. In apparatus for treating liquid with gas, a tank adapted to contain liquid, stationary oppositely positioned injectors in the lower portion of the tank adapted to inject a mixture of gas and liquid from their interiors in substantially horizontal streams into the surrounding liquid, said injectors having both their liquid inlets and their liquid outlets in communication with the tank, and means for supplying gas under pressure to said injectors.
2. In apparatus for treating liquid with gas, a tank adapted to contain liquid, a plurality of stationary hollow members submerged in the liquid in the lower portion of

the tank having outwardly directed liquid discharge passages with both ends in communication with the tank and gas passages communicating with the liquid discharge 5 passages, said hollow members being arranged so that ejected streams of gas and liquid from the respective hollow members will be directed toward one another, and means for supplying gas under pressure to 10 said hollow members.

3. In apparatus for treating liquid with gas, a tank adapted to contain liquid, hollow stationary gas injectors in the lower portion of the tank adapted to receive liquid 15 from the tank and to eject a mixture of gas and liquid from their interiors into the surrounding liquid in the tank, said injectors being arranged so that issuing streams of gas and liquid from oppositely positioned injectors will penetrate one another, and means for supplying gas to said injectors. 20

4. In apparatus for treating liquid with gas, a tank adapted to contain liquid, a stationary injector within the tank submerged 25 in the liquid, vertical liquid inlets communicating with the tank and with the interior of the injector and horizontal outlets communicating with the interior of the injector and with the tank, and means for 30 supplying gas under pressure to the interior of the injector and ejecting it with liquid through the horizontal outlets into the surrounding liquid in the tank.

5. In apparatus for treating liquid with 35 gas, a tank adapted to contain liquid, a sta-

tionary injector within the tank submerged in the liquid, a vertical liquid inlet communicating with the source of liquid supply and with the interior of the injector, a substantially horizontal liquid outlet communicating 40 with the interior of the injector and with the tank, a gas supply pipe within the vertical liquid inlet adapted to deliver gas to the horizontal outlet, and means for supplying gas under pressure to said gas pipe. 45

6. In apparatus for treating liquid with gas, a tank adapted to contain liquid, a stationary injector within the tank submerged in the liquid, a liquid inlet communicating with the source of liquid supply and with 50 the interior of the injector, a plurality of liquid outlets supplied with liquid through said inlet communicating with the interior of the injector and with the tank, and means for introducing gas under pressure into the 55 liquid outlets of the injector.

7. In apparatus for treating liquid with gas, a tank adapted to contain liquid, a stationary injector within the tank submerged 60 in the liquid having a plurality of outwardly directed discharge passages communicating through a common center with the source of liquid supply, means for combining a stream of gas with a stream of liquid in the interior of the injector and ejecting the stream of gas and liquid into the surrounding liquid in the tank, and means for supplying gas 65 under pressure to the interior of the injector.

WILLIAM E. GREENAWALT.
